UNITED STATES PATENT OFFICE

JAMES S. REID, OF CLEVELAND, OHIO, ASSIGNOR TO THE EATON AXLE & SPRING COMPANY, OF CLEVELAND, OHIO, A CORPORATION OF OHIO

CLOSURE

Application filed August 15, 1929. Serial No. 386,130.

This invention relates to closure devices, and more particularly to an improved form of cap or closure for use on filler necks of automobile gasoline tanks, radiators, and the like.

5 An object of this invention is to provide an improved form of cap or closure in which reenforcing means provided for the beaded and knurled portions is housed within the closure body.

10 Another object of this invention is to provide an improved form of cap or closure having a rigid backing member for supporting those portions of the closure body upon which beading and knurling operations are performed.

15 The invention may be further briefly summarized as consisting in certain novel combinations and arrangements of parts hereinafter described and set out in the appended claims.

20 In the accompanying sheet of drawings forming a part of this application,

Fig. 1 is a bottom plan view of my closure;

25 Fig. 2 is a top plan view of my closure with parts thereof broken away;

Fig. 3 is a sectional view taken on line 3—3 of Fig. 2;

30 Fig. 4 is a side elevation with parts broken away, showing the closure applied to a filler neck;

Fig. 5 is a detail showing the reenforcing member in elevation; and

35 Fig. 6 is a detail showing one of the closure body parts in sectional elevation.

40 Referring now in detail to the drawings, I show a closure having a body formed of separate parts secured together by a beading operation, and provided with a backing member which serves as an anvil for the beading operation. In illustrating the principle of my invention, I have shown a closure which is adapted to be connected to a tubular member by means of a bayonet joint, but, obviously, my invention is not limited in its application to the particular form of closure illustrated but may be embodied in various types of closures.

45 In the embodiment of my invention herein illustrated, the closure body is a hollow structure made up of an upper or cover part 10,

a lower or skirt part 11, and a bottom part 12, all permanently secured together. The skirt part 11 is provided with an annular flange 13 which is concentric with and surrounds an annular flange 14 formed on the bottom part 12. These annular flanges are retained in engaging, concentric relation by deforming or beading the annular portion 15 of the cover part around the annular flange 13, as clearly shown in Fig. 3. The central portion of the bottom part 12 is provided, in this instance, with a cup-shaped depression 16 upon which is carried a locking member 17, and an extension member 18. The locking member is provided with resilient fingers 19 which extend laterally through openings formed in the side wall of the extension member 18 and releasably engage inclined cam surfaces 20 formed on the tubular filler neck 21. The closure is applied to the 70 filler neck by inserting the extension into the filler neck opening and rotating the closure relative to the neck, whereupon the locking fingers engage and follow the inclined cam surfaces, causing the gasket 22 to be compressed between the bottom part of the closure and the end of the filler neck.

75 The closure body is formed of shell-like sheet metal stampings which, as previously stated, are secured together by a beading operation, and to prevent these stampings from being distorted during the beading operation, I provide a rigid reenforcing or backing member 23 which is received within the ring formed by the annular flange 14, and after 80 the parts have been assembled is wholly enclosed within the closure body. This rigid backing or reenforcing member serves as an anvil so that sufficient pressure can be applied to the body parts for beading these parts together without danger of the shell-like closure body structure collapsing or being distorted. This backing member also serves as an anvil for the knurling 24 which is applied to the periphery of the cover part to facilitate grasping the closure for rotating the same relative to the filler neck.

85 The backing member 23 is preferably formed as a solid metallic block, so that, in addition to serving as an anvil for the bead-

ing and knurling operations, this member will also add weight to the shell-like closure body structure. This additional weight facilitates the handling of the closure in applying the same to the filler neck, and also has a tendency to prevent the closure from working or jarring loose from the filler neck.

While I have shown and described the device of my invention in a detailed manner, it should be understood that I do not desire to limit myself to the precise details shown and described, but regard my invention as including such changes and modifications as do not involve a departure from the spirit of my invention and the scope of the appended claims.

Having thus described my invention, I claim:

1. In a closure for a tubular member, the combination of a body comprising parts secured together by a beading operation, locking means for releasably securing said closure on said tubular member, and a member within said body adapted to form an anvil for said beading operation.

2. In a closure for a member opening, the combination of a body comprising separate parts beaded together, locking means for releasably securing said closure and said member together, and backing means for reinforcing the beaded portions of said parts.

3. In a closure for a member opening, the combination of a body comprising metal stampings having deformed portions securing said stampings together, means for releasably holding said closure against said member opening, and a rigid member enclosed by said stampings for reinforcing said deformed portions.

40 In testimony whereof, I hereunto affix my signature.

JAMES S. REID.
